ABSTRACT

A device for application of substance to a human body surface comprising an applicator portion, the applicator portion having a topically applied substance support surface, and the topically applied substance support surface having an outer portion and a gripping portion. A personal hygiene or other topically applied substance is secured to the topically applied substance support surface on the applicator portion of said base. The applicator portion defines a top surface and at least one extension, the extension being configured to allow the substantially unobstructed flow of molten personal hygiene or topically applied substance radially outwardly toward the outer portion of the topically applied substance support surface. The extension defines at least a portion of the topically applied substance support surface. A protective member, defines a closed compartment protecting and housing the personal hygiene or topically applied substance.

**CROSS REFERENCE TO RELATED
APPLICATIONS**

This application is a continuation-in-part of U.S. patent application Ser. No. 16/719,736 filed Dec. 18, 2019, entitled Travel Size Deodorant Dispenser with Improved Cap, issued as U.S. Pat. No. 11,219,295, which is a continuation-in-part of abandoned U.S. patent application Ser. No. 15/965,171 filed Apr. 27, 2018, entitled Travel Size Deodorant Dispenser, the priority of which applications is hereby claimed. The disclosures of the aforementioned applications are hereby incorporated by reference.

TECHNICAL FIELD

The invention relates to apparatus and methods for the delivery of deodorant to the surface of the skin of a human user.

**STATEMENT REGARDING FEDERALLY
SPONSORED RESEARCH OR DEVELOPMENT**

(Not applicable)

BACKGROUND OF THE INVENTION

Today, people are exceedingly busy in attending to business matters and often have to rush between multiple appointments. Often, this does not leave much time for the luxury of returning home to freshen up. Accordingly, such products are of increasing importance.

Additionally, a high-paced, mobile lifestyle, involving such things as airline flights, road trips and the like, does not lend itself well to carrying large hygiene product containers, such as a conventional deodorant product, which can open, and under certain circumstances, spill while they are inside bags and briefcases. Therefore, a need exists for a small, single use deodorant applicator which can be easily concealed, even in a small pocket, yet safe for transport due to an individually sealed, portable design.

SUMMARY OF THE INVENTION

In accordance with the invention, an apparatus for the delivery of deodorant to the surface of the human body is provided. It comprises an applicator portion to which is secured a gel or solid deodorant and which is coupled to a handle portion. The applicator portion is sized to accommodate a single application of deodorant in a compact format while the handle portion is sized to be grasped between the fingers and thumb of a human hand. The handle portion comprises a flexible connecting point allowing the handle portion to traverse between a storage position and a gripping position during use.

The invention comprises an apparatus for the application of a gel or solid deodorant substance or other personal hygiene or topical substance to the surface of a human body. In accordance with the invention, a base comprises an applicator portion. The applicator portion has a deodorant support side, a gripping portion, and a deodorant substance secured to the applicator portion of the base. The base and deodorant substance form the applicator and an enclosure defining a compartment houses the base and the deodorant substance.

2

The applicator portion of the base comprises a matrix of recesses to which the deodorant substance is affixed. The matrix of recesses defines an array of narrow elongated contours at least some of which extend at least partially around one or more of others of the narrow elongated contours. Each of the narrow elongated contours defines a recess defined by facing sidewalls which extend at an angle with respect to the deodorant support side and face the sidewalls engaging the deodorant substance. The handle is coupled to the gripping portion of the base. The enclosure comprises a plastic film. The handle comprises a rigid grip dimensioned to be grasped between the fingers and thumb of a human hand. A mounting member coupled to the base and rotatably supporting the rigid grip enables the rigid grip to move between a storage position and a gripping position. The mounting member of the apparatus is mounted on the base by mounting pins allowing the flexible mounting member to rotate around the mounting pins in an arc. A support member is also coupled to the base to allow the applicator portion to stably sit flat on a surface when the rigid grip is in the storage position.

The handle of the apparatus may comprise a cloth member comprising a gripping end protruding from the gripping portion of the base and dimensioned to be grasped between the fingers and thumb of a human hand and a mounting end coupled to the gripping portion of the base.

The handle may also comprise two gripping members protruding from the base. The gripping members define a finger hole passing through the gripping member. The hole is sized to allow a finger or thumb of a human hand to be inserted within the finger hole. The gripping members comprise a flexible mounting member coupled to the base which allow the gripping members to traverse between a storage position and a gripping position. The base and handle are made of plastic injection molded from a single piece of plastic.

BRIEF DESCRIPTION OF THE DRAWINGS

40 The operation of the invention will become apparent from the following description taken in conjunction with the drawings, in which:

FIG. 1A is a side view outlining the basic elements of the invention in which the applicator portion and handle portion 45 may be understood;

FIG. 1b is a cross-sectional view of the support base and supported deodorant material along lines 1b-1b of FIG. 3 corresponding to a cross-sectional view defined by the intersection of a plane perpendicular to the plane roughly defined by the support and a plane perpendicular to and passing through the center of the support;

FIG. 2 is a diagram of a rigid handle system embodiment of a handle portion of the invention;

FIG. 3 is a diagram of a coupling system comprising a rigid handle system and the base of the applicator portion of the invention;

FIG. 4 is a diagram of an alternate mounting method of a rigid handle system coupled to the base of the applicator portion of the invention;

FIG. 5 is a diagram of a possible storage configuration for the invention in which a rigid handle system is stowed into a recess in the underside of the base of the applicator portion of the invention;

FIG. 6 is a diagram of an alternate mounting configuration for a handle portion of the invention;

FIG. 7 is a diagram of another alternate cloth handle portion of the invention;

FIG. 8 illustrates the use of the above mentioned alternate cloth handle portion of the invention;

FIG. 9 is a diagram of yet another alternate handle portion comprising a pair of loops;

FIG. 10 shows the use of the above mentioned alternate handle portion comprising a pair of loops;

FIG. 11 is a diagram of an array of indentations across the application surface of applicator portion of the invention;

FIG. 12 is a diagram of rings of deodorant anchored between an array of raised rings on the applicator surface of the applicator portion of the invention;

FIG. 13 is a sectional side-view of a living hinge embodiment of the applicator of the present invention with the grasping handle illustrated in solid lines with the handle moved in the direction of the arrow in the use position, and in phantom lines with the handle in the folded storage position;

FIG. 14 is an enlarged view of the living hinge;

FIG. 15 is a side view of the inventive applicator;

FIG. 16 is a view of an alternate living hinge embodiment of a handle of the invention with two small living hinges;

FIG. 17 is a perspective view of the inventive applicator showing the deodorant-receiving surfaces;

FIG. 18 is a perspective view of the inventive applicator with a cover placed over the deodorant deposited on the applicator;

FIG. 19 is a sectional view of the cover;

FIG. 20 is an enlarged sectional view of the cover, illustrating the edge of the base and cover;

FIG. 21 is a top view of the cover;

FIG. 22 is a perspective view of the inventive applicator with a cover placed over the deodorant deposited on the applicator;

FIG. 23 is a top view of the cover;

FIG. 24 is an alternate embodiment of a top view of the deodorant-receiving surfaces;

FIG. 25 is a side view of a living hinge applicator;

FIG. 26 is a top view of a bottom portion of the applicator;

FIG. 27 is a side view of a living hinge embodiment of the applicator of the present invention with the grasping handle;

FIG. 28 is an isometric bottom view of a living hinge embodiment of the deodorant dispenser of the present invention closed with a cap and with a handle in a use position attached to the base;

FIG. 29 is an isometric bottom view of the deodorant dispenser with removed cap separated by moving the cap translationally downwards away from the applicator and with a grasping handle in the use position attached to the base;

FIG. 30 is an isometric bottom view of the deodorant dispenser closed with a cap and with a handle in the storage position attached to the base;

FIG. 31 is an isometric top view of the deodorant dispenser closed with a cap and with a handle in the use position attached to the base;

FIG. 32 is a cross sectional view of the deodorant dispenser closed with a cap and with a handle in the use position attached to the base;

FIG. 33 is a cross sectional view of the deodorant dispenser without a cap and with a handle in the use position attached to the base;

FIG. 34 is a diagrammatic view showing the seal between cap and deodorant dispenser;

FIG. 35 is a top view of an alternate embodiment of the invention showing the deodorant receiving surfaces;

FIG. 36 is an isometric view from the bottom of the inventive deodorant dispenser in the closed position with its cap in place and with a handle in the storage position attached to the base; and

FIG. 37 is an alternate embodiment of a cross sectional view of the deodorant dispenser with the cap closing the deodorant containing compartment and with the handle in the use position attached to the base.

DETAILED DESCRIPTION OF THE PREFERRED EMBODIMENTS

Referring to FIG. 1a, an overview of a single-use deodorant applicator may be understood. The single-use deodorant applicator 2 comprises a circular base 4 composed of plastic in accordance with a preferred embodiment, or, alternatively, metal. Base 4 is rigid and functions as a foundation upon which the rest of the device is constructed. The top of circular base 4 comprises a series of raised rings 6 as well as corresponding circular channels 8. Raised rings 6 and circular channels 8 are shaped and spaced in such a way that deodorant, in either gel or solid form, can be affixed to base 4 with the deodorant utilizing raised rings 6 and circular channels 8 as an adherence surface. A plastic or metal handle 10 is coupled to the underside of base 4 such that handle 10 can swivel out from a position lying flat against base 4 (as illustrated in phantom lines), to a position perpendicular or nearly perpendicular to the bottom surface of base 4 for use, or swivel in, parallel to the bottom surface of base 4 for storage.

FIG. 1b illustrates the placement of deodorant material 52 in channels 8 in the form of rings of deodorant material. It will be understood from the figures that successive rings are positioned at different heights from the bottom of base 4. The outermost rings of deodorant material 52 are relatively low and the central deposition of deodorant material 53 is in the highest position. Accordingly, together rings of deodorant material 52 and the central circular deposition of deodorant material 53 generally defined a convex or domed configuration.

Referring to FIG. 2, the construction of handle 10, and how handle 10 attaches to base 4, may be better understood. Handle 10 is constructed in a semi-circular shape. Handle 10 made sized such that it can fold back against base 4 without protruding. Two mounting holes 12 pass completely through mounting arms 14, which extend past base 4 on either side of the attaching end of handle 10. The mounting arms 14 and handle 10 are formed in a single injection molded plastic member, adding strength and simplicity to the design. The mounting holes 12 allow the handle 10 to be attached to base 4 of the single-use deodorant applicator through the use of mounting pins 15 (FIG. 1 b), which will be described in greater detail below.

Referring to FIG. 3, a connection assembly attaching handle 10 to base 4 may be understood in greater detail. The handle 10 connects to base 4 such that handle 10 can be quickly snapped into place during component assembly. The component assembly process involves aligning mounting arms 14 of handle 10 perpendicular to the bottom of base 4 such that mounting holes 12 of mounting arms 14 are positioned just below a pair of mounting pins 15 protruding from base 4. The mounting pins 16 protrude from base 4 such that they are always in line with holes 12 in mounting arms 14, when properly mounted inside mounting holes 12. The mounting pins 15 are positioned such that it is possible for handle 10 to traverse a semi-circular arc defined in the direction of arrows 18, thus allowing the orientation of

handle 10 to traverse such arc from a flat starting position against the bottom of base 4 to a finishing position which is perpendicular to the bottom of base 4. Deodorant material 52 (FIG. 1a) of conventional design is deposited in circular channels 8.

Referring to FIG. 4, an alternate mounting method for handle 110 may be understood. Once again, handle 110 is attached to base 104 similarly to handle 10 (FIG. 3) thus allowing handle 110 to traverse in an arc from a flat position against base 104 to an extended position which is perpendicular to base 104. The mounting pins 115 are coupled to base 104 and are located inside a recess 120 on the bottom of base 104, thus allowing handle 110 to fold inside base 104 for compact storage with minimal or no protrusion from base 104. The recess 120 is shaped to match the shape of handle 110 such that handle 110 fits snugly inside recess 120 without sticking such that handle 110 may be easily extended along the arc defined by the movement of handle 110, as it may be moved by the use of, for example, a human finger.

Referring to FIG. 5, it may be understood how handle 110 fits snugly inside recession 120 of base 104 when handle 110 is in a closed position. In this diagram, it is shown how handle 110 protrudes slightly from recess 120 in the bottom of base 104 such that a finger may make easier contact with handle 110. The configuration diagrammed in FIG. 5 allows for a larger contact surface between handle 110 and a human finger while still providing a thin profile for compact storage. If no protrusion is desired, handle 110 may made thinner.

Also referring to FIG. 5, an optional storage packet may be used to contain the apparatus. Such storage packets may be a conventional form, for example, similar to those used to house condiments such as ketchup and mustard. In accordance with the invention, such a storage packet may be formed in a conventional manner, for example being formed by a pair of facing planar film members. More particularly, a container may be formed by a planar bottom layer 121 and a planar top layer 123. Planar bottom layer 121 and planar top layer 123 may be made of a polymer, such as a simple plastic film as is used to house ketchup. Alternatively, metallized polymer layers may also be employed. In accordance with the invention, it is contemplated that planar bottom layer 121 and planar top layer 123 would have a thickness in the range of 2-7 thousandths of an inch.

In the case of a simple polymer layer of the type used to house ketchup in individual single servings, planar bottom layer 121 and a planar top layer 123 may be formed into a packet by being heat-sealed around their edges 125 (FIG. 5a). As is apparent from the figures, planar bottom layer 121 and planar top layer 123 are substantially the same size and larger than the inventive applicator 110. Accordingly, planar bottom layer 121 and planar top layer 123 extend beyond the edge of both the length and width of the applicator 110. The peripheral portions of planar bottom layer 121 and a planar top layer 123 are fused together, for example, using heat around the edge of the apparatus to form an airtight, single-use container similar to a ketchup packet. The result is a sealed unit 125 containing applicator 110. Sealed unit 125 includes serrations 127 in a manner typical of such packets.

It is noted that while the use of such a package is illustrated only in FIG. 5, it may be understood this packet can be used to house any of the other variations of the inventive apparatus as illustrated in the figures herein.

In accordance with the invention, it is contemplated that a plurality of applicators 110 would be contained each in its own container 123, perhaps packaged in a larger box con-

taining a half-dozen or several dozen packaged applicators. When it is desired to use one of these devices to apply deodorant, the package is split between the serrations 127 using the fingernails, torn open and the deodorant applicator 110 is removed and used as described herein.

Referring to FIG. 6, an alternate mounting configuration for handle 10 may be understood. A cylindrical mounting protrusion 222 extends from the bottom of base 4 such that it is possible to align mounting holes 12 of mounting arms 14 with mounting pin 224 of mounting protrusion 222. The mounting pin 224 along the length of mounting protrusion 222, perpendicular to the circular faces of the cylinder and, therefore, parallel to the bottom of the base 4. When the mounting holes 12 of the mounting arms 14 are properly aligned with the mounting hole 14 of the mounting protrusion 222, handle 10 rotates on pins 224. Thus, handle 10 may easily be snapped into place, similar to the process described with respect to FIG. 3, and may further rotate freely after being snapped into place.

Also referring to FIG. 6, the circular ring system of ridges and channels involved in the mounting of gel or solid deodorant may be understood. The raised rings 6 and circular channels 8 are all formed from the same plastic member that comprises base 4 during the fabrication process of, for example, injection molding. Furthermore, the mounting protrusion 222 can be formed from the same plastic mold as well during the fabrication process with the mounting pin 224 B. As a result of the fabrication process, the raised circular rings 6 and circular channels 8 form a mounting surface for a gel or solid deodorant 52 such that the tops of the channels 8 are nearly slanted extending from but not quite perpendicular to the base 4, thus providing sufficient friction to hold a gel or solid deodorant in place. Because the inner rings 6 and channels 8 protrude higher from the base 4 than the outer rings 6 and channels 8, it is possible for the single-use deodorant applicator 202 to conform to various human body surfaces more easily.

Referring to FIG. 7, an alternate handle system 334 may be understood. In this alternate handle system, a flexible or semi-rigid handle 34 is cut to shape from a sheet of cloth or plastic. The handle 334 comprises an attachment end 336 on one side and a gripping end 338 on the other side. The attachment end 336 is affixed along a joinder line 337 to the bottom of the single-use deodorant applicator 302 using some form of adhesive such as glue or tape. The gripping end 338 protrudes from the side of the single-use deodorant applicator 302 to a sufficient distance such that the gripping end 338 may be easily grasped by the fingers of a human hand. The handle 334 is sufficiently thin to allow for compact packaging. Accordingly handle 334 can be folded behind the single-use deodorant applicator 302 for compact packaging.

Referring to FIG. 8, the use of the alternate handle system 334 may be understood. As mentioned above, the gripping end 338 of the handle 334 protrudes from the side of the single-use deodorant applicator 302. This allows the fingers of a human hand to easily grasp the handle 334 between them with thumb 340 pressing against the top side of handle 334 and finger 342 pressing against the bottom side of handle 334. This method allows finger 342 to act as a guide for the single-use deodorant applicator 302 while deodorant is being applied to the human body by providing moderate pressure to rub the top surface of the single-use deodorant applicator 302 against the skin surface to which the user wishes to apply deodorant.

Referring to FIG. 9, an alternate handle system 444 may be understood. The handle system 444 comprises two plastic

loops, loop 446 and loop 448, which are made from the same plastic material of which the single-use deodorant applicator 402 is made. This means that no special attachment system is required. Instead, the handle system 444 is formed at the same time as the single-use deodorant applicator 402 in a single molding or stamping process. This eliminates the need for complicated manual assembly while allowing for many instances of the single-use deodorant applicator 402 to be created simultaneously, in accordance with the manufacturing process to be described below. Loop 446 and loop 448 are flexible enough to be bent backwards below the base of the single-use deodorant applicator 402 for gripping by the thumb and finger of a human hand during use.

Referring to FIG. 10, the use of the alternate handle system 444 may be understood. The single-use deodorant applicator 402 is gripped by folding loop 446 and loop 448 backwards below the base of the single-use deodorant applicator 402. The thumb 440 is then inserted into the loop 446 while the finger 442 is inserted into the loop 448. The thumb 440 and the finger 442 are then pinched together, thus creating enough tension and friction to hold the single-use deodorant applicator 402 in place and allow for controlled movement during deodorant application to a human body during use.

Referring to FIG. 11, a method for securing deodorant in a gel or solid form may be understood. A series of indentations 550 are distributed over the surface area of the single-use deodorant applicator 502 in which deodorant 552 in a gel or solid form may be inserted. The indentations are deep enough to provide a sufficient anchor for the deodorant.

Referring to FIG. 12, the anchoring of a gel or solid deodorant 52 within an array of raised rings 6 may be understood. The deodorant 52 is applied between each of the raised rings 6 such that the deodorant 52 protrudes slightly above the upper surface of the raised rings 6. During the application process, the deodorant 52 will transfer to a contacted human skin surface. Since the human skin surface is flexible, the skin can be pressed in between the raised rings 6, during application, as the vertical height of the deodorant 52 is reduced during use.

Referring to FIG. 13, a sectional side-view of an alternative embodiment of the deodorant applicator 610 is shown. In accordance with the invention, it is noted that applicator 610 is manufactured in the configuration illustrated in solid lines in FIG. 13. After the same is manufactured, handle 620 is folded to the position illustrated in phantom lines after which the same may be packaged in a flat envelope like container. In use, after removal of applicator 610 from the package, handle 620 is pulled from the position illustrated in phantom lines in FIG. 13 to the position illustrated in solid lines.

Handle 620 is formed integrally with base 612 and a living hinge 622, which joins the handle to base 612. The living hinge 622 allows for the handle 620 to be folded up into the base 612 for packaging. When the user opens the package to use the deodorant applicator, the user can fold the handle 620 out of the base 612, such that the handle 620 is substantially perpendicular to the base 612, allowing the user to grasp the handle 620 and use the deodorant applicator 610. The living hinge is a more cost-effective and efficient option.

The figure also shows the raised rings 614 and corresponding circular channels 616. Raised rings 614 and circular channels 616 are shaped and spaced in such a way that deodorant can be affixed to base 612 with the deodorant utilizing raised rings 614 and circular channels 616 as an adherence surface.

The dimension of the largest rings may be in the range of about one and three-quarter inches in diameter, or about 4 centimeters. The height of the applicator may be about 0.3 inches or about 7 mm. The height of the deodorant may have a total thickness of about 3.5 mm, or about 2.5 mm in the circular channels and about 1 mm over the top of the ridge.

FIG. 14 is an enlarged view of the living hinge 622. A first surface 624 is defined on the living hinge 622. The first surface 624 has a first width. A second surface 626 is defined on the living hinge 622, directly opposite the first surface 624. The second surface 626 has a second width, which is narrower than the first width. The first width is larger to better allow the handle 620 to be bent at the living hinge 622 towards the base 612 on the side of the first surface 624. The lack of material in the location of the first surface 624 provides for the adjacent portions of the living hinge 622 and handle 620 to be compressed as the handle 620 is being folded in towards the base 612 in the direction opposite that of the arrow in FIG. 13. The narrower, second width is present in order to allow the handle 620 to fold, towards the first surface 624, in to the base 612.

FIG. 15 displays a side view of the living hinge applicator 610. The shape of the handle 620 can be seen from this view. The shape of the handle 620 gives the user a substantial area to grasp, giving the user a better grip while applying the deodorant.

FIG. 16 displays an alternative embodiment of the inventive living hinge applicator 710. Alternative applicator 710 comprises a handle 720 and a base 712, which are substantially the same as handle 620 and base 612 of the embodiment of FIG. 13. The embodiment in FIG. 16 is essentially the same as living hinge 610 except there are two living hinges 728 and 730 which are a relatively narrow dimension. In accordance with the invention, one may have more than two living hinges.

Returning to the embodiment of FIG. 15, FIG. 17 displays a perspective from the top of applicator 610 which is substantially the same as the top of applicator 710. This view shows the raised rings 614 and corresponding circular channels 616.

FIG. 18 illustrates another perspective view of applicator 610, but with a cover 632 disclose over its top surface to protect the deodorant material from being dislodged. Cover 632 is placed over base 612 (as seen in FIG. 13). Cover 632 has a protruding handle 638 which allows the user to remove cover 632 from base 612 (as seen in FIG. 13).

Cover 632 also comprises two holes 634 and 636. These holes serve a several distinct purposes. When the deodorant material is heated and in a liquid state it can be injected through holes 634 and 636 and onto the surface of deodorant applicator 610. In addition, cover 632 keeps deodorant applicator 610 substantially sealed and therefore protects the deodorant substance from dislodgement and deformation. Cover 632 holds the deodorant material in place when, after injection into covert applicator 610, it is in liquid form. This allows it to cool and harden in place over the raised rings 614 and corresponding circular channels 616. The cover 632 also protects the appearance of the product, for example in the event that the product is crushed. A sticker (not illustrated) may then be applied to cover 632 over holes 634 and 636 with a, for example, circular shape to match the cover 632 or other shape, sealing holes 634 and 636 on cover 632. Cover 632 thus provides a rigid protective member over the deodorant substance and base 612. The sticker also acts to seal the deodorant substance such that no substances can enter through the two holes 634 and 636.

The cover has a small tab 638 for the purpose of allowing one to rip cover 632 and take the cover off base 612. The base may also have a similar small tab such that the tabs can be worked against each other, aiding in the process of removing cover 632 from base 612. During manufacture, it is possible to create a specified angular orientation of one tab with respect to the other. For example, to off-set the two tabs, for example by 2-30° such that it is easy to push on one with the thumb of one hand and the other with the index finger of the same hand. Alternatively, the cover can be manufactured such that it can be rotated on the base, thus allowing the user to deviate the tabs to any angle he/she prefers.

FIG. 19 shows a sectional side-view of base 612 and cover 632. This view shows holes 634 and 636 passing completely through cover 632.

FIG. 20 shows an enlarged sectional view of cover 632 and internal circumferential contours for receiving base 612. This view is of the region at the region of engagement between the edge of base 612 and cover 632 where protruding handle 638 is located. Protruding handle 638 is part of cover 632. When the user lifts up protruding handle 638, protruding handle 638 and cover 632 are pulled up and away from base 612, creating space between base 612 and cover 632. This allows the cover 632 to be removed from base 612.

FIG. 21 displays a top view of cover 632. This view shows the location of holes 634 and 636.

It is contemplated that the deodorant dispenser, with or without the cap, may be stored and transported in any suitable package. The package may be a ketchup-packet-type package, whereby the deodorant dispenser may be packaged in the same manner as is illustrated in FIG. 5. Alternatively, the deodorant dispenser, with or without the cap, can be included in one compartment of a two-compartment package.

In accordance with this last embodiment, the second compartment may contain a wipe, for example a conventional wipe with an alcohol-based cleaning material to allow the individual to clean him/herself before applying the deodorant. The packet may have a dimension of about 6 cm square, or perhaps slightly longer on one side and may be comprised of first, second and third heat sealable sheets, we need applicator between the first and second sheets and the wipes between the second and third heat-sealable sheets. The deodorant support may have a dimension of approximately 4.5 cm.

Referring to FIGS. 22-23, views of an alternative embodiment of the deodorant applicator 810 is shown, with a cover 832 disclosed over its top surface to protect the deodorant material from being dislodged. Cover 832 has a protruding handle 838. Protruding handle 838 has a hole 839 which allows the user to attach applicator 810 to other things such as a backpack, clothing, etc. Cover 832 also comprises hole 833 which may be used to inject deodorant material, in liquid state, onto the surface of the deodorant applicator 810. The deodorant material may be any prior art deodorant material or alternatively the inventive dispenser may be used for another personal care product such as moisturizer, lip protectant cosmetic or other personal care product, provided the same has the characteristic of becoming fluid enough (e.g. by melting) to be poured or injected into the inventive applicator.

Cover 832 comprises notches 854 located on the side 855 of top cover 832. Notches 854 allow for user to more easily dislodge top cover 832 from base 812. Cover 832 may also have arrows 841 which illustrate, to the user, the direction in which the cover 832 may be moved to dislodge top cover 832 from base 812.

Although top cover 832, as shown in FIGS. 22-23, is round shaped, top cover 832 can have different shapes. In addition, a sticker (not illustrated) may be applied to cover 832, over hole 833. The sticker may be shaped to match the shape of top cover 832, sealing hole 833 and protecting the deodorant substance.

FIG. 24 illustrates the top view of base 812 of applicator 810 with cover 832 removed. The figure also shows the raised rings 814 and corresponding channels 816. Raised rings 814 and channels 816 are shaped and spaced in such a way as to allow for deodorant material 52 to be affixed to base 812 by utilizing raised rings 814 and channels 816 as an adherence surface. Deodorant material 52 may be deposited onto base 812 to form a flat surface or it may be deposited onto base 812 to form a convex or domed configurations. Such configurations allows for easier application of the product onto the skin of the user.

The outermost rings of deodorant material 52 are relatively low and the central deposition of deodorant material 53 is in the highest position. Accordingly, together rings of deodorant material 52 and the central circular deposition of deodorant material 53 generally defined a convex or domed configuration.

FIG. 25 displays a side view of the living hinge applicator 810. The shape of the handle 820 can be seen from this view. The shape of handle 820 is substantially the same as handle 620, as shown in FIG. 15. Handle 820 comprises a protruding handle notch 856.

FIG. 26 is a top view of the bottom portion 813 of applicator base 812. Bottom portion 813 has an opening 817 that is sized to fit notch 856 when handle 820 is moved in the direction of the arrow, as illustrated in FIG. 27. Notches 854 that are located on cover 832 have hollow spaces 858, configured to the same size as notch 856 located on handle 820 as well as opening 817 located on the bottom portion 813 of applicator base 812.

Referring to FIG. 27, when user finishes applying the topical substance held by applicator base 812, the user places cover 832 onto applicator base 812 and rotates cover 832 in clockwise direction to seal it onto applicator base 812. At that point, the handle 820 is substantially perpendicular to the base 812. The user then moves handle 820 to be folded to the base 812 allowing for notch 856 to be coupled to the hollow space 858 (not illustrated in FIG. 27) through opening 817. This allows for the cover 832 to be securely locked to the applicator base 812 preventing the cover 832 from dislodging from base 812.

Alternatively, notches 854 may have the hollow spaces 858 configured so that notch 856 is coupled with one of hollow spaces 858 even if base 812 does not comprise opening 817.

Referring to FIG. 28, a particularly advantageous embodiment of the invention is illustrated. A single-use deodorant dispenser 910 is composed of plastic in accordance with this preferred embodiment of the invention. Alternatively, other materials may be used, such as polymeric composites, for example composites incorporating fibers such as graphite or fiberglass, or metal.

Deodorant dispenser 910 comprises an applicator 918 and a cap 932. Applicator 918 and cap 932 together form a container for containing the material to be dispensed, such as deodorant, sunscreen, antibiotic, anesthetic, poison ivy treating, bug repellent, antihistamine, skin moisturizer, cortisone or allergic reaction treating materials.

The material being applied by dispenser 910 is contained within dispenser 910, having been deposited therein as is detailed below. The applicator 918 comprises a rigid base

11

912 which functions as a foundation upon which the rest of the device is constructed and a handle 920 attached to applicator base 912. In accordance with the present invention, half disc shaped gripping portion of handle 920, together with handle base 911 and living hinge portion 922 are manufactured as a separate part, for example by injection molding plastic into a mold. Handle base 911 is secured to the underside 923 of applicator base 912.

During use, the user rotates handle 920 angularly from the flat position (FIG. 30) to the position illustrated in FIG. 28. Cap 932 is then unscrewed and removed to expose the material to be applied, allowing use of the material by application to, for example, the skin, by the user holding extended out handle 920 while smearing the material onto the skin. The user, after application, places cap 932 onto applicator base 918 and rotates cap 932 in the clockwise direction to seal it onto applicator base 912, protecting the material until the next use.

Base 912 is disc shaped and its diameter can vary between 12 and 110 millimeters and its thickness 913 (FIG. 32) may vary typically from 1 to 2 mm, or it may have any thickness sufficient to result in substantial rigidity of the base in its role of supporting the material being dispensed (for example deodorant or sunscreen). Base 912 must stably support the material being dispensed during application to the skin.

In accordance with the preferred embodiment, the base has a diameter ranging between 12 mm and 110 mm. The material receiving volume must be sufficient to receive the material being dispensed with an average thickness 947 ranging between 1 mm and 14 mm. More preferably the base has a diameter ranging between 20 mm and 80 mm with a material receiving volume having an average thickness 947 ranging between 2 mm and 10 mm. Most preferably, the base has a diameter ranging between 25 mm and 60 mm with a material receiving volume having an average thickness 947 ranging between 3 mm and 8 mm, or perhaps ideally between 4 and 6 mm.

In accordance with the invention, it is contemplated that deodorant dispenser 910 has an internal volume 948 (FIG. 31), which comprises a volume 951 (which houses the actual material being applied) (FIG. 32) located above arcuate walls 914 which receives the material to be dispensed and has an average thickness 947. Internal volume 948 further comprises an additional volume 953 which is defined in between arcuate walls 914, which holds material which provides a support function for the material (located above the arcuate walls 914) being applied.

As illustrated in FIG. 29, base 912 comprises a cylindrical side wall 945 which includes threads 931 on the radially outer surface of side wall 945. Thread 931 is configured to mate with a mating thread 943, located on the radially inside surface 935 of a cap side wall 955 of cap 932.

Cap 932 further comprises an annular sidewall 947 (diagrammatically shown in FIG. 34) positioned radially inward with respect to cap side wall 955 (FIG. 29). Referring to FIG. 29, when cap 932 is tightly screwed into applicator 918, top surface 963 of annular sidewall 947 and bottom surface 965 (FIG. 33) of side wall 945 sealingly contact each other. More particularly, when cap 932 is screwed onto applicator 918, referring back to FIG. 34, top surface 963 advances in the direction of arrow 967, from the position shown in solid lines, toward bottom surface 965 of annular sidewall 947, to the position shown in dashed lines, to provide engagement between the two surfaces 963 and 965. This provides for sealing the contents of the inventive container.

12

More particularly, in accordance with one embodiment of the present invention, the slanted surface 970 of wedge 968 may be driven against the corner 966 of surface 965. In this case, the result is slight deformation of corner 966 and the confirmation of corner 966 and slanted surface 970 assures a high quality seal. This results in very effective sealingly securing cap 932 on applicator 918.

In accordance with the present invention, cap 932 has eight securing positions. That is, when cap 932 is to be screwed in all the way, it can be positioned in eight different ways relative to applicator 918 and handle 920, as will be detailed below in connection with the description of FIG. 30.

Referring to FIG. 29, handle 920 comprises a mounting hinge base member 911 and rigid gripping portion 929. Handle 920 further comprises a living hinge 922, which connects the mounting member 911 to the rigid gripping portion 929. Mounting hinge base member 911 is attached to the underside of base 912 by a heat weld or any other suitable means. Living hinge 922 allows rigid gripping portion 929 to swivel out from a position lying flat against base 912 (FIG. 30), to a position roughly perpendicular or nearly perpendicular to the bottom surface of base 912. This provides for convenient gripping during use. After use or while it is, for example, inside a consumer package, rigid gripping portion 929 may be positioned parallel to the bottom surface of base 912.

When it is desired to use the deodorant dispenser, the user can rotate handle 920 away from base 912, such that handle 920 is substantially perpendicular to the base 912, allowing the user to grasp the handle 920 and use the deodorant applicator 918. After use, it may be rotated back to the storage position illustrated in FIG. 30.

Referring back to FIG. 29, rigid gripping portion 929 comprises a prong 956 used to lock gripping rigid gripping portion 929 in the storage position (FIG. 30) by being snapped into one of the eight sockets 954 (FIG. 29). Rigid gripping portion 929 further comprises studs 919 configured to be positioned inside pockets 939 of the base 912 when rigid gripping portion 929 is in storage position. Studs 919 coupled with pockets 939 provide a fictional gripping surface to more securely hold rigid gripping portion 929 when rigid gripping portion 929 is in the storage position.

Referring to FIG. 30, an isometric bottom view of the deodorant dispenser 910 with a cap 932 secured in position closing dispenser 910 is illustrated. Handle 920 in the storage position is illustrated. After deodorant 910 is manufactured and cap 932 is tightly screwed into the applicator 918, handle 920 is folded to the position illustrated. When handle 920 is in the storage position, deodorant dispenser 910 may be packaged in a flat envelope like container. One of the sockets 954 receives the prong 956 of handle 920 when handle 920 is in the storage position. Depending on how the user engages cap 932 and applicator 918, one of the sockets 954 will be positioned to receive the prong 956 when cap 932 is tightly secured on the applicator 918. Each socket 954 can be positioned to receive the prong 956.

Sockets 954 contain indents 951 best seen in FIG. 29 which when coupled with notches 957 of the prong 956 secure handle 920 in storage position. Sockets 954 protrude beyond cylindrical wall 955 thus forming gripping parts which allow the user to more easily dislodge cap 932 from applicator 918.

The thickness 961 (FIG. 30) of the outer surfaces of the deodorant dispenser with closed cap 932 and handle 920 in the storage position may vary and be in the range between 5 mm and 30 mm. More preferably thickness 961 is ranging

between 5 mm and 25 mm. Most preferably, the thickness 961 is ranging between 8 mm and 12 mm.

Referring to FIG. 31, an isometric top view of deodorant dispenser 910 with cap 932 screwed into the applicator 918 and handle 920 in the gripping position is illustrated. Cap 932 has arrows 941 which illustrate, to the user, the direction in which cap 932 is rotated to dislodge cap 932 from applicator 918. When deodorant dispenser 910 is manufactured, cap 932 is screwed into the applicator 918. After closure of the applicator by cap 932, solidifying liquid or gel material to be applied 949 (FIG. 32) is filled, while still liquid, into internal volume 948 through a hole 933 in cap 932. Once internal volume is sufficiently filled with the liquid or gel material to be applied, a self-adhesive sticker 969 (FIG. 31) shown in dashed lines is attached to surface 970, sealing the material in the inventive dispenser 910. Sticker 969 is made, for example, of plastic or paper, and has glue on the side that engages surface 970 which results in sealing hole 933.

Material to be applied 949 is best seen in FIG. 32, where a cross sectional view of the deodorant dispenser with a closed cap 932 and handle 920 in gripping position is illustrated. As is illustrated, arcuate walls 914 are perpendicularly oriented with respect to and attached to the base 912. Liquid or gel material to be applied is affixed to the base 912, radially inner surface of side wall 945 and arcuate walls 914.

The height of arcuate walls 914 increases as the radius decreases. That is arcuate walls 914 positioned closer to the line 960 have greater height than arcuate walls positioned further from the line 960. In accordance with the present invention, heights of the arcuate walls may vary between 30% and 80% of the height of the space between the top and the bottom of the inner volume. More preferably heights of the arcuate walls may vary between 35% and 70% of the height of the space between the top and the bottom of the inner volume. Most preferably, heights of the arcuate walls may vary between 45% and 60% of the height of the space between the top and the bottom of the inner volume.

An isometric top view of the applicator 918 is illustrated in FIG. 33 where the shape of the arcuate walls 914 can be better understood. Arcuate walls 914 are formed by dividing a ring into a four equal size arcs. The number of rings divided by equal size segments can vary and be, for example, between 1 and 20 or any other number rings that will provide substantial surface area to affix the material to be applied 914 and prevent it from detaching while deodorant dispenser 910 is being used or stored. In accordance with the preferred embodiment, there are five raised rings and each ring is divided into four segments of equal length forming arcuate walls 914. The thickness of the arcuate walls 914 may vary and be in the range, for example, 0.1-2 mm. More preferably, the thickness of the arcuate walls 914 is ranging between 0.1 mm and 1 mm. However, these dimensions are not very critical.

Arcuate walls 914 are shaped and spaced in such a way that the material to be applied 914, in either gel or solid form, can be affixed to the applicator 918 with the deodorant engaging arcuate walls 914, top surface of base 912 and sidewall 945 as an adherence surface. Radius of the arcuate walls 914 may vary and increases by equal increments in order to radially uniformly distribute rings on the surface of the base 912 as illustrated in FIG. 33. In accordance with the particular embodiment, the diameter of the smallest arcuate wall 914 is 7.1 mm and increases by 6.7 mm increments. That is the radii of the arcuate walls from smallest to largest

are 7.1 mm, 13.8 mm, 10.5 mm and 27.2 mm, respectively, in accordance with the preferred embodiment. However, the same is not critical.

The manufacturing of the single-use deodorant applicator 2 is done by injecting plastic into a mold. Alternatively, the desired member may be made by blow forming and die cutting a sheet of plastic. Multiple members may be formed simultaneously across the width of a plastic sheet web in a continuous blow forming process, thus allowing for mass production. Further, applicator 2 may be made of polypropylene or other materials having characteristics similar to polypropylene.

While the above description of the embodiments focuses on deodorant, other personal hygiene or topical products may be used as well. For example, personal hygiene or topical products such as anti-perspirants, sunscreens, lip balm, fragrance, pain-relievers such as IcyHot®^{TM}, anti-chafing balm such as Glide®^{TM}, etc. may be used.

In accordance with the embodiment of the invention illustrated in FIGS. 35-37, the locking of the handle in the storage position is maintained in position by a pair of snap engagement surfaces as will be discussed in detail below. Referring to FIG. 36, in the present embodiment, when handle 1020 is in the storage position, where it bears against the bottom of the applicator base 1018, handle 1020 is held in that position (the position illustrated in FIG. 36) by a pair of circumferentially extending engagement members 1071. Engagement members 1071 bear circumferentially extending nibs 1076 which extend towards each other so that the distance between them is slightly less than the width of tab 1079 on handle 1020, thus allowing handle 1020 to flexibly be driven into the slot where it is retained by circumferentially extending nibs 1076. This provides a securement surface and has the advantage of assuring alignment during manufacture as compared to the previous embodiment, which relied upon being in the proper radial position with respect to the base during the filling operation. Also, the tolerances are more forgiving because there is no prong that needs to be aligned with a socket. When handle 1020 is in the storage position, the applicator base 1018 is able to stably sit flat on a surface because of support member 1072.

In addition to the use of circumferentially extending engagement members 1071 and circumferentially extending nibs 1076 that keep handle 1020 in place when handle 1020 is in the storage position (FIG. 36), as compared to the use position illustrated in FIG. 37, in order to ensure the freshness of the deodorant (or other material, such as lip balm, moisturizer, or the like), the inventive dispenser 1010 features raised radial members 1014 which define radial channels 1015. Radial members 1014, disposed on the applicator base 1012 of the deodorant applicator 1010, take the form of raised radial members 1014 (FIG. 35). More particularly, in accordance with this embodiment of the invention, the raised radial members 1014 have a straight configuration and are oriented radially, which promotes the flow of liquified deodorant material 1049 (FIG. 37), when the molten material is poured into applicator/container 1010 through hole 1033 in cap 1032 of inventive deodorant dispenser 1010. During filling the molten material pours down through hole 1033 and flows outward radially toward the radially inner surface of sidewall 1045 of inventive deodorant or other material dispenser 1010.

The use of radially oriented raised radial members 1014 combats the tendency of material being filled into the dispenser of the previous embodiments to be slowed down by the obstructing effect of circumferential material retaining extensions of the prior embodiments. The flow was

15

somewhat slowed, during the filling process on account of the arcuate walls blocking the flow of liquified deodorant material towards the inner surface of the sidewall of the deodorant dispenser. This decline in flow rate results in solidification before the deodorant material fully fills the deodorant dispenser.

In accordance with the preferred embodiment of the invention, flow is promoted by radially oriented raised deodorant retaining raised radial members 1014 (FIG. 37), which allow flow of material therebetween, thus speeding up the flow and assuring that the deodorant dispenser 1010 will be filled more evenly. In addition, the increase in deodorant material 1049 (higher capacity is also possible because of the radial structure, as discussed below) being poured into the deodorant dispenser 1010 at a quicker rate results in overall thermal energy (i.e. a higher temperature, in the liquified deodorant material 1049 being at a higher value) which further impedes solidification and promotes flow. In other words, the liquified deodorant material 1049 is maintained at a higher temperature during filling because more material is flowing in and because it is flowing in more quickly toward the edges of the container.

As alluded to above, because of the improved flow of material, it is also possible to increase the size of the deodorant dispenser 1010. For example, one can fill a container where the height 1075 of the container cap 1032 is 12.5 mm and its diameter is 48 mm, corresponding to a material containing compartment having an approximate height of 11 millimeters and a diameter of 40 millimeters. As a result, more of the liquified material 1049 may be poured into the container, thus increasing the value of the product.

Referring to FIG. 36, yet another difference in the preferred embodiment of FIGS. 35-37, is the provision of a support member 1072. Support member 1072 allows the deodorant dispenser 1010 to sit flat on a surface when the handle 1020 is in the storage position illustrated in FIG. 36. A further improvement in the preferred embodiment of FIGS. 35-37 is the removal of the sockets on the cap 1032, which is a material savings. The loss of extra grip is not viewed as significant.

Referring to FIG. 37, finally yet a further improvement in the preferred embodiment is the provision of a tapered thickness in the top surface of the cap 1032. More critically, as material is flowing through the hole 1033 in cap 1032 during filling of the deodorant dispenser 1010 (which is closed during the filling process (i.e., the cap 1032 is screwed down tightly onto the applicator base 1012 (FIG. 36)) that holds the deodorant material 1049) the air in deodorant dispenser 1010 tends to be driven outward by the liquified deodorant material 1049. In practice, it was found that air bubbles formed at the top of the deodorant dispenser against the inner top surface of the cap 1032. By providing for a cap 1032 with an inner top surface which is higher in the center than it is at the sides, the small difference in height promotes the migration of bubbles toward the center of the cap 1032 allowing air to escape through the opening in the cap 1032, allowing a more complete filling of the inventive applicator. In practice, it has been found that a top member having a thickness of 0.635 mm in the center 1074 and a thickness of 1.7 mm closer to the circumference 1073 provides a sufficient slope to achieve the migration of air bubbles toward the center.

While illustrative embodiments of the invention have been described, it is noted that various modifications will be apparent to those of ordinary skill in the art in view of the above description and drawings. Such modifications are

16

within the scope of the invention which is limited and defined only by the following claims.

What is claimed:

- 5 1. Apparatus for the application of a personal hygiene or other topically applied substance to the surface of the human body comprising:
  - (a) a base, comprising:
    - (i) an applicator portion, said applicator portion having a topically applied substance support surface, said topically applied substance support surface having an outer portion; and
    - (ii) a gripping portion, said applicator portion being attached to said gripping portion;
  - (b) a personal hygiene or other topically applied substance secured to the topically applied substance support surface on said applicator portion of said base, said base and said personal hygiene or topically applied substance forming an applicator, said applicator portion defining a top surface and at least one raised member, said raised member being configured to allow the substantially unobstructed flow of molten personal hygiene or topically applied substance radially outwardly toward the outer portion of said topically applied substance support surface, said raised member defining at least a portion of said topically applied substance support surface; and
  - (c) a protective member, defining a closed compartment protecting and housing said personal hygiene or topically applied substance.
- 10 2. Apparatus as in claim 1, further comprising an engagement member secured to said applicator portion, and wherein said gripping portion comprises a handle pivotally mounted to said applicator portion, said handle comprising a mating engagement member which mates with and may be secured by said engagement member to put the handle in the retracted position.
- 15 3. Apparatus as in claim 2, further comprising a support member configured and dimensioned to support the apparatus when the handle is in the retracted position.
- 20 4. The apparatus of claim 2, wherein said at least one raised member, overlies a substantial portion of said top surface of said applicator portion.
- 25 5. Apparatus as in claim 1, further comprising an engagement member secured to said applicator portion, and said handle comprising a mating engagement member, and wherein said gripping portion is integrally formed with said applicator portion, said engagement member and said mating engagement member during an injection molding process.
- 30 6. An applicator as in claim 1, wherein the gripping portion is joined to said applicator portion by a living hinge.
- 35 7. Apparatus as in claim 1, wherein the at least one raised member is oriented radially.
- 40 8. An applicator for the application of a paste-like self-supporting deodorant material to the skin of the human body comprising:
  - (a) a base comprising:
    - (i) an applicator portion, said applicator portion having a deodorant support surface; and
    - (ii) a gripping portion, said applicator portion being integrally formed with said gripping portion;
  - (b) a deodorant substance secured to the deodorant support surface on said applicator portion of said base, said base and deodorant substance forming an applicator, said deodorant substance extending beyond a plurality

of raised members, said deodorant substance together with said applicator portion defining a deodorant assembly height; and

- (c) a protective member having a protective member height and defining a closed compartment protecting and housing said deodorant substance, wherein said applicator portion of said base comprises retention structure forming a matrix of recesses to which said deodorant substance is affixed, a portion of said deodorant substance being positioned within said recesses and other portions of said deodorant substance positioned between said applicator portion and said protective member, and wherein said protective member lockingly engages said base, said deodorant having a height which allows said deodorant to be contained within protective member, 15 wherein said retention structure comprises said plurality of raised members which extend from said deodorant support surface, said members defining the matrix of recesses, said deodorant substance extending at least in part into said recesses, said deodorant substance being retained proximate said deodorant support surface by said recesses, and
- wherein said applicator portion defines a sidewall for containing deodorant material, and wherein said protective member is a cap defining a hole for receipt of molten deodorant material, and wherein at least some of said plurality of raised members are positioned adjacent to each other, adjacent elongated members defining channels which extend with a component extending from said hole to said sidewall. 25

9. An applicator as in claim 8, wherein said applicator portion has a securement surface opposite said deodorant support surface, said securement surface supporting said gripping portion, said gripping portion comprising a retractable handle secured to said securement surface and further comprising a support member configured and dimensioned to support the applicator when the gripping portion is adjacent the securement surface. 35

10. An applicator for the application of a paste-like substantially self-supporting deodorant material to the skin of the human body comprising:

- (a) a base comprising:
- (i) an applicator portion, said applicator portion having a deodorant support surface; and
  - (ii) a gripping portion, said applicator portion being integrally formed with said gripping portion;
- (b) a deodorant substance secured to the deodorant support surface on said applicator portion of said base, said base and deodorant substance forming an applicator, said deodorant substance extending beyond a plurality of raised members; and
- (c) a protective member defining a closed compartment protecting and housing said deodorant substance, wherein said applicator portion of said base comprises a retention structure forming a matrix of recesses to which said deodorant substance is affixed, a portion of said deodorant substance being positioned within said recesses and other portions of said deodorant substance positioned between said applicator portion and said protective member, and wherein said protective member lockingly engages said base, and wherein said retention structure comprises said plurality of raised members which extend from said deodorant support surface, said members defining the matrix of recesses, said deodorant substance extending at least in part into said recesses, said deodorant substance being retained

proximate said deodorant support surface by said recesses, wherein said applicator portion defines a sidewall for containing deodorant material, and wherein said protective member is a cap defining a hole for receipt of molten deodorant material, and wherein at least some of said plurality of raised members are positioned adjacent to each other, adjacent elongated members each defining channels which extend with a component extending from said hole to said sidewall.

11. An applicator for the application of a paste-like self-supporting deodorant material to the skin of the human body comprising:

- (a) a base comprising:
- (i) an applicator portion, said applicator portion having a deodorant support surface; and
  - (ii) a gripping portion, said applicator portion being integrally formed with said gripping portion;
- (b) a deodorant substance secured to the deodorant support surface on said applicator portion of said base, said base and deodorant substance forming an applicator, said deodorant substance extending beyond at least one raised member; and
- (c) a protective member defining a closed compartment protecting and housing said deodorant substance, wherein said applicator portion of said base comprises retention structure forming a matrix of recesses to which said deodorant substance is affixed, a portion of said deodorant substance being positioned within said recesses and other portions of said deodorant substance positioned between said applicator portion and said protective member, and wherein said protective member lockingly engages said base, wherein said applicator portion has a securement surface opposite said deodorant support surface, said securement surface supporting said gripping portion, said gripping portion comprising a handle secured to said securement surface by a living hinge, and further comprising handle engagement structure on said gripping portion, and securement surface engagement structure on said securement surface, said handle engagement structure mating with said securement surface engagement structure, whereby said gripping portion may be positioned extending from said securement surface or positioned proximate said securement surface, said handle engagement structure and said securement surface engagement structure being positioned to engage and mate with each other when said gripping portion is proximate said securement surface whereby said gripping portion may be retained in place proximate said securement surface.

12. An applicator as in claim 11, further comprising a support member configured and dimensioned to support the applicator when the gripping portion is adjacent the securement surface.

13. The applicator of claim 11, further comprising:

- (d) an annular sidewall extending from and secured to said applicator portion, said annular sidewall being disposed around said applicator portion.

14. The applicator of claim 13, wherein said protective member is a cap, said cap comprising (i) a cap top with a periphery, (ii) a cap sidewall extending from the periphery of the cap top, said cap sidewall having an inner circumferential surface, and (iii) cap screw threads disposed on said inner circumferential surface of said cap sidewall, further comprising a circumferential applicator sidewall extending from said applicator portion, and said applicator sidewall having an outer circumferential surface, said outer circum-

19

ferential surface having mating applicator screw threads which mate with said cap screw threads disposed on said inner circumferential surface of said cap sidewall.

15. An applicator for the application of a paste-like self-supporting cosmetic material to the skin of the human body comprising:

(a) a base comprising:

(i) an applicator portion, said applicator portion having a cosmetic support surface, wherein said cosmetic support surface comprises at least one raised member, which extends from said cosmetic support surface;

(ii) said at least one raised member being configured to allow the flow of a molten self-supporting cosmetic material across the cosmetic support surface; and

(iii) a gripping portion, said gripping portion being integrally formed with and foldably joined to said applicator portion, whereby said gripping portion may be advanced toward said applicator portion to reduce the volume occupied by said applicator;

(b) a self-supporting cosmetic substance secured to the cosmetic support surface on said applicator portion of said base, said base and self-supporting cosmetic substance forming an applicator, said self-supporting cosmetic substance extending beyond said at least one raised member, said self-supporting cosmetic substance being at least in part positioned between and retained by said at least one raised member, and said self-supporting cosmetic substance defining a cosmetic substance height; and

(c) a protective member having a protective member height and defining a closed compartment protecting and housing said self-supporting cosmetic substance, wherein said at least one raised member defines a retention structure forming a matrix of recesses to which said self-supporting cosmetic substance is affixed, a portion of said self-supporting cosmetic substance being positioned within said recesses and other portions of said self-supporting cosmetic substance positioned between said applicator portion and said protective member, said protective member having a height which allows said cosmetic substance to be contained within said protective, said protective member lockingly engaging said base.

16. Apparatus as in claim 15, wherein said base defines a circumferential portion proximate a periphery of said cosmetic support surface and a central portion proximate a center of said cosmetic support surface, and said at least one raised member extends partially between said circumferential portion and said central portion.

17. Apparatus as in claim 15, wherein said protective member is a cap sealed to said applicator portion by a chamfered surface, said cap having a height roughly equal to the height of the self-supporting cosmetic substance, said cap being locked into position by a locking structure selected from the group consisting of a screw thread or a bayonet structure.

18. An applicator for the application of a cosmetic material as in claim 15, further comprising:

(d) support member positioned, configured and dimensioned to support the applicator when the gripping portion is adjacent the securement surface.

19. An applicator for the application of a cosmetic material as in claim 11, further comprising:

(e) handle engagement structure on said gripping portion; and

20

(f) securement surface engagement structure on said securement surface, said handle engagement structure mating with said securement surface engagement structure, said handle engagement structure and said securement surface engagement structure being positioned to engage and mate with each other when said gripping portion is proximate said securement surface whereby said gripping portion may be retained in place proximate said securement surface.

20. An apparatus for the application of a paste-like self-supporting cosmetic material to the skin of the human body comprising:

(a) a base comprising:

(i) an applicator portion, said applicator portion having a cosmetic support surface, wherein said cosmetic support surface comprises a plurality of raised members which extend from said cosmetic support surface; and

(ii) a gripping portion, said gripping portion being integrally formed with and joined to said applicator portion;

(b) a self-supporting cosmetic substance secured to the cosmetic support surface on said applicator portion of said base, said base and self-supporting cosmetic substance forming an applicator, said self-supporting cosmetic substance extending beyond said raised members, said self-supporting cosmetic substance being at least in part positioned between and retained by said raised members; and

(c) a protective member defining a closed compartment protecting and housing said self-supporting cosmetic substance, wherein said raised members define a retention structure forming a matrix of recesses to which said self-supporting cosmetic substance is affixed, a portion of said self-supporting cosmetic substance being positioned within said recesses and other portions of said self-supporting cosmetic substance positioned between said applicator portion and said protective member, and wherein said protective member lockingly engages said base, wherein said gripping portion and said applicator portion are joined by a living hinge, allowing said handle to move freely between a position that is perpendicular to said base and proximate to said base.

21. Apparatus for the application of a paste-like self-supporting cosmetic material to the skin of the human body comprising:

(a) a base comprising:

(i) an applicator portion, said applicator portion having a cosmetic support surface, wherein said cosmetic support surface comprises a plurality of raised members which extend from said cosmetic support surface; and

(ii) a gripping portion, said gripping portion being integrally formed with and joined to said applicator portion;

(b) a self-supporting cosmetic substance secured to the cosmetic support surface on said applicator portion of said base, said base and self-supporting cosmetic substance forming an applicator, said self-supporting cosmetic substance extending beyond said raised members, said self-supporting cosmetic substance being at least in part positioned between and retained by said raised members; and

(c) a protective member defining a closed compartment protecting and housing said self-supporting cosmetic substance, wherein said raised members define a retention structure forming a matrix of recesses to which said self-supporting cosmetic substance is affixed, a

21

portion of said self-supporting cosmetic substance being positioned within said recesses and other portions of said self-supporting cosmetic substance positioned between said applicator portion and said protective member, and wherein said protective member lockingly engages said base, further comprising an enclosure, said base, said cosmetic substance and said protective member being positioned within said enclosure, said enclosure comprising a pair of facing plastic film members, said facing plastic film members being secured to each other along peripheral portions of said facing plastic film members to form said enclosure.

22. An applicator for the application of a paste-like self-supporting cosmetic material to the skin of the human body, comprising:

(a) a base comprising:

(i) an applicator portion, said applicator portion having a cosmetic support surface, and a securement surface opposite said self-supporting cosmetic support surface; and

(ii) a gripping portion, said gripping portion being integrally formed and foldably joined with said applicator portion, said securement surface supporting said gripping portion, and said gripping portion comprising a handle secured to said securement surface;

(b) a self-supporting cosmetic substance secured to the cosmetic support surface on said applicator portion of said base, said base and self-supporting cosmetic substance forming an applicator, said self-supporting cosmetic substance extending beyond at least one raised member; and

(c) a protective member defining a closed compartment protecting and housing said self-supporting cosmetic substance, wherein said applicator portion of said base comprises retention structure forming a matrix of recesses to which said self-supporting cosmetic substance is affixed, a portion of said self-supporting cosmetic substance being positioned within said recesses and other portions of said self-supporting cosmetic substance positioned between said applicator portion and said protective member, and wherein said protective member lockingly engages said base; and

(d) support member positioned, configured and dimensioned to stably support the applicator when the gripping portion is adjacent the securement surface.

23. An applicator as in claim 22, wherein said protective member comprises a protective member sidewall and a protective member top, said protective member top defining a hole, and said retention structure is configured and oriented to promote the flow of molten self-supporting cosmetic substance from said hole toward an outer portion of said applicator portion.

24. An applicator as in claim 23, wherein said protective member top is thinner adjacent said hole.

25. An applicator as in claim 22, further comprising an engagement structure secured to said securement surface on said applicator portion for engaging said gripping portion at the position where said gripping portion is adjacent said securement surface.

26. An applicator for the application of a paste-like self-supporting cosmetic material to the skin of the human body comprising:

(a) a base comprising:

(i) an applicator portion, said applicator portion having a cosmetic support surface; and

22

(ii) a gripping portion, said applicator portion being integrally formed with said gripping portion;

(b) a self-supporting cosmetic substance secured to the cosmetic support surface on said applicator portion of said base, said base and self-supporting cosmetic substance forming an applicator, said self-supporting cosmetic substance extending beyond at least one raised member; and

(c) a protective member defining a closed compartment protecting and housing said self-supporting cosmetic substance, said protective member comprising a sidewall and a top member joined to said sidewall and defining a hole proximate a central portion of said top member, the top member having portions proximate said hole, portions of said top member proximate said hole being thinner than portions of said top member located proximate said sidewall, wherein said applicator portion of said base comprises a retention structure forming a matrix of recesses to which said self-supporting cosmetic substance is affixed, a portion of said self-supporting cosmetic substance being positioned within said recesses and other portions of said self-supporting cosmetic substance positioned between said applicator portion and said protective member, and wherein said protective member lockingly engages said base.

27. An applicator for the application of a paste-like self-supporting cosmetic material to the skin of the human body, comprising:

(a) a base comprising:

(i) an applicator portion, said applicator portion having a cosmetic support surface, and a securement surface opposite said cosmetic support surface; and

(ii) a gripping portion, said applicator portion being integrally formed with said gripping portion, said securement surface supporting said gripping portion, and said gripping portion comprising a handle secured to said securement surface;

(b) a self-supporting cosmetic substance secured to the cosmetic support surface on said applicator portion of said base, said base and self-supporting cosmetic substance forming an applicator, said self-supporting cosmetic substance extending beyond at least one raised member; and

(c) a protective member defining a closed compartment protecting and housing said self-supporting cosmetic substance, wherein said applicator portion of said base comprises a retention structure forming a matrix of recesses to which said self-supporting cosmetic substance is affixed, a portion of said self-supporting cosmetic substance being positioned within said recesses and other portions of said self-supporting cosmetic substance positioned between said applicator portion and said protective member, and wherein said protective member lockingly engages said base; and

(d) a living hinge supporting said gripping portion to said securement surface, whereby said gripping portion may be positioned extending from said securement surface or positioned proximate said securement surface;

(e) handle engagement structure on said gripping portion; and

(f) securement surface engagement structure on said securement surface, said handle engagement structure mating with said securement surface engagement structure, said handle engagement structure and said securement surface engagement structure being positioned to engage and mate with each other when said gripping

23

portion is proximate said securement surface whereby said gripping portion may be retained in place proximate said securement surface.

28. An apparatus for the application of a cosmetic material to the surface of the human body comprising:

(a) a base portion defining:

- (i) a cosmetic support surface defined by a plurality of raised members, secured to said base portion whereby the extensions define an array of recesses configured to promote the radial flow of a molten cosmetic substance from a central portion of said recesses to the periphery of said recesses;
- (ii) an opposite surface supporting a gripping portion, the gripping portion comprising a living hinge secured to said opposite surface and a handle secured to said living hinge; and
- (iii) a pair of nibs rigidly secured with respect to said opposite surface, wherein the handle is integrally joined to and collapsible against the opposite surface, and wherein the handle can lockingly engaged to the pair of nibs when collapsed;

5

10

15

24

- (b) a deodorant or cosmetic substance affixed to said cosmetic support surface; and
- (c) a protective member secured to said base portion and defining a containment volume, said containment volume extending beyond said deodorant or cosmetic substance, said protective member being lockingly engageable to the base portion.

29. The apparatus of claim **28** wherein said base portion further comprises a support member, said support member being integrally formed to said base portion at a height equivalent to the height of the handle in the collapsed position.

30. The apparatus of claim **29** wherein said base portion comprises threads which threadingly engage mating threads on said protective member.

31. The apparatus of claim **28** wherein said protective member contains a hole whereby said molten cosmetic substance can be filled and whereby there is a thinning of the protective member adjacent to said hole.
